UNITED STATES PATENT OFFICE.

CHARLES P. LESHER, OF LANSING, MICHIGAN.

CIGAR-MOLD PRESS.

SPECIFICATION forming part of Letters Patent No. 278,245, dated May 22, 1883.

Application filed August 8, 1882. (No model.)

To all whom it may concern:

Be it known that I, CHARLES P. LESHER, of Lansing, in the county of Ingham and State of Michigan, have invented certain new and useful Improvements in Presses for Cigar-Molds; and I do hereby declare the following to be a full, clear, and exact description of the invention, such as will enable others skilled in the art to which it pertains to make and use 10 the same.

My invention relates to presses for cigar-molds, the object being to provide a device of this character of simple, effective, and durable construction, adapted to be readily attached 15 to the under side of a chair or work-bench, whereby the pressing may be accomplished without the necessity of the workmen leaving their seats.

The invention consists in combining with a 20 chair or bench a cigar-mold press, as herein-after fully described.

The invention further consists in the details of construction and combinations of parts hereinafter fully described, and pointed out in 25 the claims.

In the drawings, Figure 1 represents a perspective view of a chair provided with my improvement. Fig. 2 is a vertical section of my improved press. Fig. 3 is a perspective view 30 of the under side of the table or platen of the press. Fig. 4 represents a perspective view of the frame or casing of the press, and Fig. 5 represents one of the operating-levers detached.

35 A represents the frame or casing of the press, consisting of an upper plate, *a*, adapted to be rigidly secured to the under side of a seat, and depending arms *a'* are connected at their lower ends by cross-bars *a''*. At each 40 of the four corners of the frame is formed a bearing, *a''*. Said bearings receive the fulcrums of the operating-levers of the press.

B represents the bed or platen of the press, provided with lugs *b* to guide the bed between 45 the arms of the frame. The under side of said bed or platen, Fig. 3, is provided near each end with two parallel inclined planes, *C*, and stop-lugs *D*. E E represent parallel ribs or tracks adapted to serve as guides for 50 the rollers of the operating-levers.

F F represent operating-levers, consisting of diverging arms upwardly turned and forked to form bearings for an anti-friction shaft, *G*, carrying rollers *g g*, the latter being adapted to travel upon the inclined planes of the platen 55 B. Each arm of the lever F is provided with an outwardly-projecting lug or journal, *f*. These lugs are fulcrumed in the bearings *a''* of the frame, as before explained.

H H represent thumb-screws projecting 60 through the bottoms of the bearings *a''* of the frame, to impinge against the fulcrums of the levers for the purpose of raising said levers, as may be desired, to press molds of different sizes. 65

The operation of the press as thus described is as follows: The mold containing the bunches is placed upon the platen B, and the levers are drawn up until their short arms pass the center of gravity, when they will be retained by 70 the resistance of the mold until released.

It will be observed that by the arrangement of the press beneath a chair, as shown, the workman secures the advantage of his sitting position, and the work is thus greatly facilitated, and the press may be operated with the minimum effort, as the levers project from each side of the seat, where they may be conveniently grasped by the workman. 75

Having fully described my invention, what I 80 claim as new, and desire to secure by Letters Patent, is—

1. The combination, with a workman's seat, of a press for cigar-molds, secured to the under side of said seat, and adapted to be operated by hand, substantially as set forth. 85

2. The combination, with a workman's seat, of a press for cigar-molds, secured to the under side of said seat, and provided with operating-levers projecting from either side of the 90 seat within easy reach of the workman, substantially as set forth.

3. The combination, with a workman's seat, of a press consisting of a frame secured to the under side of the seat, and formed with bearings for the fulcrums of operating-levers, and a bed or platen arranged within said frame, and hand-levers provided with anti-friction shafts, substantially as set forth. 95

4. The combination, with the frame, of a bed 100

or platen provided on its under side with inclined planes and stops, and operating-levers fulcrumed in bearings of the frame, and provided with anti-friction rollers adapted to travel on said inclined planes, substantially as set forth.

5. The combination, with the frame adapted to be secured beneath a workman's seat, of a platen provided at its edges with lugs to guide it upon the frame, and on its under side with inclined planes, stop-lugs, and parallel ribs, and operating-levers, whose short arms are forked to receive anti-friction shafts, substantially as set forth.

6. The combination, with the frame provided with bearings and thumb-screws, of a movable platen, and operating-levers, each consisting of a handle and two diverging arms, and each of said arms having a lug or journal, and forked to receive an anti-friction shaft, substantially as set forth.

CHARLES P. LESHER.
